FOREIGN PATENT DOCUMENTS

JP D1479595 * 9/2013

Primary Examiner — Lakiya Rogers*Assistant Examiner* — Altaira Swangin(74) *Attorney, Agent, or Firm* — Schiff Hardin LLP(57) **CLAIM**

We claim the ornamental design for an “instrument panel for an automobile” thereof, as shown and described.

DESCRIPTION

FIG. 1 is a front perspective view for an “instrument panel for an automobile” showing my new design,

FIG. 2 is a front view thereof,

FIG. 3 is a rear view thereof,

FIG. 4 is a top view thereof,

FIG. 5 is a bottom view thereof,

FIG. 6 is a left-side view thereof; and,

FIG. 7 is a right-side view thereof.
